UNITED STATES PATENT OFFICE

CHAUNCEY R. MANN, OF TROY, NEW YORK

GAME APPARATUS

Application filed March 29, 1930. Serial No. 439,993.

This invention relates to a game apparatus which may be used indoors or outdoors as a means of recreation or exercise. The apparatus comprises a unitary structure preferably rectangular and box-like in shape and of a size made convenient for the parlor, gymnasium, or the athletic field. It is used in conjunction with one or more spherical objects such as bowling balls, marbles, or the like, one of which when forcibly directed toward the apparatus by the physical acumen of the player, is adapted to encounter an obstacle and then enter one of a number of holes in the top of the apparatus, as will be fully described hereinafter.

In the prior art, a number of proposals have been made for games and game devices where balls are used in conjunction with nets or other receiving means. One of such proposals is the "ski-ball" game in which a ball delivered by the player toward an objective point encounters a hump so that an aerial trajectory results. These proposals, however, concern apparatus rather expensive to construct because of the alleys, nets, cages and other incidents connected therewith and furthermore, are not unitary in structure; i. e., the various parts are separate entities. In such prior devices also, the ball has been given a trajectory such that it is adapted to either land in a receptacle inclined to the vertical or else its trajectory has been obstructed by a ceiling in order to deflect the ball into a horizontal receptacle.

My apparatus differs from these in that it is a unitary structure, comparatively simple and inexpensive, and the ball is given a vertically disposed trajectory by virtue of the odd shape of the preliminary obstacle that it encounters, thus permitting the use of a horizontal receptacle without any deflecting media.

In the drawings, Figure 1 is a perspective view of my apparatus;

Figure 2 is a plan view showing the perforated top plate marked up for playing baseball;

Figure 3 is a view in sectional elevation taken along the line 3-3 of Figure 2.

Referring to the drawings, the numeral 1

represents a box-like frame with a cutout portion 2 and a curved apron-holding portion 3. Braces 4 and 5 strengthen the structure.

Secured to the curved portion 3 is the apron 6 having a curvature specifically shown in Figure 3. Supported by suitable means is the top plate 8 with circular perforations 9 and cutout corners 10. The member 11 is suitably supported in an inclined position and serves as a ball return.

The invention as shown is especially designed for playing baseball and is preferably played as follows:

A ball is propelled from some predetermined distance away from the device which rests in a horizontal position on the floor or the ground. When the ball strikes the apron 6, it is given an aerial trajectory and descends upon the plate 8, either rolling off at 4 or bouncing off the same or entering any one of the holes. The inclined plate 11 returns the ball so that it can easily be removed from the receptacle. As shown, the top plate 8 represents a baseball diamond.

The rules of the game are as follows:

1. If the ball goes in hole 1 BH, the player has made a one base hit (and so to speak) becomes a runner on first base. A one base hit advances all runners one base.

2. If the ball goes in hole 2 BH, the player has made a two base hit (and so to speak) becomes a runner on second base. A two base hit advances all runners two bases.

3. If the ball goes in hole 3 BH, the player has made a three base hit (and so to speak) becomes a runner on third base. A three base hit advances all runners three bases.

4. If the ball goes in the hole Home run, the player has made a home run. A home run scores all runners.

5. When a player is advanced from third to home he scores one run for his team, or side.

6. If the ball goes in either hole marked 1 Strike he has one strike on himself. When he has three strikes he is out.

7. If the ball goes in either hole marked 1 Ball he has one ball on himself. When he has four balls he (so to speak) becomes a runner on first base.

8. If the ball does not go in a hole and remains on top of the board inside the field of play, the player (so to speak) is safe at first base.
9. If the ball does not go in a hole and remains on top of the board outside the field of play, it is a foul ball.
10. If the ball does not go in a hole, and rolls or bounces off the board, it is a foul ball.
11. If there is a runner on first, first and second, or on all bases, and the ball remains on top of the board in the field of play, the runner or runners advance one base.
12. Each player must roll in the order in which his name appears in the batting order.
13. Each player rolls until he is out, safe at first base or made a hit.
14. A player is out when he has three strikes. The first two foul balls each count as a strike. After having two foul balls, if the ball goes in the hole 1 Strike, the player has struck out otherwise he continues to roll until he is safe at first, made a hit or flies out.
15. A player having four balls automatically becomes a runner on first base. If first base is occupied, the runner on first goes to second.
16. When a team has three outs, the other team or side then rolls until it has three outs.
17. The game is scored in the same manner as a regular baseball game is scored.
18. If a situation arises which is not covered in the above rules, regular baseball rules will govern the decision to be made.
19. The field of play and the foul territory is divided by white lines, from home to first base and from home to third base.
20. If after the ball is rolled, it fails to hit the top of the board, it is a foul ball.
- From the above rules it is very evident that regulation baseball game can be played between two players, two regular baseball nines or two teams of an unlimited equal number of players. Where more than two players play a regular baseball score sheet should be used.
- My apparatus can be made of wood or metal, or a combination of the same, or of any other material that is durable and economical. As will be apparent to those skilled in the art, the device may be manufactured in various sizes for use in the home or indoors, and also for outdoors.
- Claim:
- In a unitary baseball game device, a box-like frame having a front apron inclined rearwardly and upwardly and formed on a curve increasing in curvature from its front edge rearwardly, a horizontal top-plate supported by the frame rearwardly to and at a higher level than the apron and having represented thereon a baseball diamond with perforations representing conventional baseball terms, a cutout portion rearwardly of the

apron and in front of the top-plate providing a space between apron and plate serving as a hazard and as a means of access to the interior of said frame, a bottom plate supported by the frame and inclined toward the front of the frame, the construction being such that a ball propelled in a longitudinal direction toward the apron will strike the same and be given a steep trajectory in a rearward direction so that it may enter a perforation in the top-plate.

In testimony whereof, I hereunto set my hand.

CHAUNCEY R. MANN.
